Primary Examiner — Steven J Czyz

(57) **CLAIM**

The ornamental design for a hat box, as shown and described.

DESCRIPTION

FIG. 1 is a front, top and right side perspective view of a hat box, showing my new design;
FIG. 2 is a front, bottom and left side perspective view thereof.

FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The broken lines in the drawings illustrate the portions of the hat box, which form no part of the claimed design.

1 Claim, 8 Drawing Sheets
